UNITED STATES PATENT OFFICE.

CHARLES E. TROWBRIDGE, OF WHITINSVILLE, MASSACHUSETTS, ASSIGNOR
TO THE WHITINSVILLE SPINNING RING COMPANY, OF SAME PLACE.

HOLDER FOR SPINNING-RINGS.

SPECIFICATION forming part of Letters Patent No. 341,076, dated May 4, 1886.

Application filed December 10, 1885. Serial No. 185,239. (No model.)

To all whom it may concern:

Be it known that I, CHARLES E. TROWBRIDGE, a citizen of the United States, residing at Whitinsville, in the county of Worcester and State of Massachusetts, have invented 5 certain new and useful Improvements in Holders for Spinning-Rings, of which the following is a specification, reference being had therein to the accompanying drawings.

10 My invention relates to holders or receivers for spinning-rings; and the objects of my improvements are to provide a holder having a broad and continuous flat surface to rest upon the rail and a bearing to uniformly support the ring all around its lower edge and clasp it exteriorly at all points thereof, and thus prevent the springing and flattening of the ring or its 15 accidental disconnection from the holder as the result of a side concussion. I attain these 20 objects by the construction illustrated in the accompanying drawings, in which—

Figure 1 is a top view of the ring and holder on an enlarged scale. Fig. 2 is a vertical central section of the same. Fig. 3 is a top view 25 of the holder with the ring removed.

The holder is specially applicable to the duplex race-ring A, made with two circular races, a, united by a short tubular neck or connection, a². This ring is not split transversely to 30 facilitate its introduction into the holder. Neither is the latter split transversely for the same purpose.

The holder B consists of a flat annulus having two notches, b, extending a short distance 35 in its edge, to receive the screws by which it is fastened to the rail of the spinning-frame. The inner edge of the annulus is flanged upward at b², uniformly all around, and the upper edge of the flange b², after having been 40 turned of a uniform height, has its inner face grooved or kerfed and slightly undercut, to produce a circular shoulder, b³, to support

the ring A, and a thin edge or flange, b⁴, to encircle the edge of the bottom race, a, of the ring A, and after said ring has been placed in 45 position with its bottom flange on the circular shoulder b³ the thin flange b⁴ is pressed down firmly against and slightly upon the bottom race, and the ring A has thus its whole bottom periphery secured to its holder. By this construction the ring is held securely all around, and is not liable to become disconnected from the holder by a side blow. The holder has no projection upon its vertical flange, against which dust and lint could collect. It is inexpensive, and bearing uniformly all around the ring prevents it from flattening, as it is important that the ring should remain perfectly 50 round.

Although a duplex race-ring is shown in 60 connection with the holder, it is evident that if the bottom inner flange of the race-ring were dispensed with its outer flange would still be as securely retained by my improved holder.

Having now fully described my invention, 65 I claim—

In combination with a race-ring flanged at the top and bottom, the holder B, consisting of a thin flat annulus provided with peripheral notches b, and having its inner edge turned 70 up uniformly all around and cut in the inner side of said edge, a circular kerfed groove having a shoulder, b³, to support the race-ring, and a thin edge or flange, b⁴, to encircle the bottom flange of said race-ring and press upon 75 and clamp it uniformly, substantially as and for the purpose described.

In testimony whereof I affix my signature in presence of two witnesses.

CHARLES E. TROWBRIDGE.
